(57) CLAIM

The ornamental design for a garden water ring, as shown and described.

DESCRIPTION

FIG. 1 is a top perspective view of a garden water ring, showing my new design;

FIG. 2 is a front elevation view thereof;

FIG. 3 is a top plan view thereof;

FIG. 4 is a right-side elevation view thereof;

FIG. 5 is a bottom plan view thereof;

FIG. 6 is a left-side elevation view thereof;

FIG. 7 is a rear elevation view thereof;

FIG. 8 is a bottom perspective view thereof; and,

FIG. 9 is a top perspective view of the garden water ring, shown with environmental structure.

The dash-dash broken lines showing stakes in FIG. 9 depicts environmental subject matter that forms no part of the claimed design, while the dot-dash broken lines shown in the drawings depict the bounds of the garden water ring that form no part of a claimed design.

1 Claim, 5 Drawing Sheets
